UNITED STATES PATENT OFFICE.

CHARLES H. KORS, OF PHILADELPHIA, PENNSYLVANIA.

BINDER.

1,314,338.

Specification of Letters Patent. Patented Aug. 26, 1919.

Application filed November 4, 1918, Serial No. 260,928.

To all whom it may concern:

Be it known that I, CHARLES H. KORS, a citizen of the United States, residing at Philadelphia, Philadelphia county, Pennsylvania, have invented a certain new and useful Improvement in Binders, of which the following is a full, clear, and exact description.

My invention relates to binding means for bundles and the like and has for its object to provide a simple and efficient binding means which can be easily applied and easily removed. It is particularly applicable for use in binding bundles of cigars and has for its object to produce binding means employing a tape or strip such that the tape or strip does not tend to become stringy or cord-like when in use as is the case where the ends of such tape or strip are secured by an ordinary knot. It further has for its object to produce a fastening device which may be used with tapes of different thicknesses. It further has for its object to produce a fastening device which may be used with a cord when desired and further to produce a fastening device which can be used with either a tape or a cord and which when used with the former does not result in forming the tape into a cord-like shape.

The method now mostly used for bundling cigars is to buy muslin or material, tear it into strips, and tie one of these strips around fifty or a hundred cigars, making an ordinary knot for securing the ends of the strip. The tying of the strips into knots in order to fasten them soon has the whole strip twisted into a cord-like form and its use has to be soon dispensed with because of the damage done to the cigars bound with such material, the cord-like form which the strip assumes resulting in too concentrated pressure upon the cigars so as to damage them.

Another method that is sometimes used is to secure the bundle by means of a strap and ordinary buckle. When this is done, the strap has to be drawn tight enough to permit the tongue of the buckle to pass through the hole in the strap. This requires a greater strain or pressure than is necessary, which is somewhat released when the tongue is inserted in the hole and often times results in too much pressure even after the tongue is inserted in the hole. It also requires an increased pressure when the strap is being unbuckled so the damage is liable to be done not only at the cigar maker's

table but also in the packing department when the bundles are opened by the packers. The damage done makes it difficult for a packer to get his proper selections and frequently results in what is known as hiding the dented cigars by burying them in the bottom of the box. Such damaged cigars often interfere with the ready sale of the goods because the smoker will not take a damaged cigar and the dealer does not feel like opening a new box until all of the old box are disposed of.

With my device, these difficulties are avoided, and further, both time and labor are saved in the securing and opening of the bundles, and, furthermore, material is saved, since the strips can be used for a longer period. In using my device, the encircling strip can be brought to the exact tension desired and fastened and unfastened without requiring any extra compression or slack for either securing or releasing. The securing means, however, is useful in other relations than in connection with cigars.

The following is a description of an embodiment of my invention, reference being had to the accompanying drawings, in which,

Figure 1 shows my securing means applied to a bundle of cigars;

Fig. 2 is a plan view of the fastening device of said securing means;

Fig. 3 is a modification of the same;

Fig. 4 is another modification of the same; and,

Figs. 5, 6 and 7 are sections of either of these devices upon the line $\alpha-\alpha$, Figs. 2, 3 and 4, showing various ways in which the strip may be inserted in the slits so as to be held therein.

Referring more particularly to the drawings, 1 is a bundle of cigars; 2 is a flat strip of cloth or tape fastened around the bundle; 3 is a fastening device for securing the ends of the strip. This fastening device consists of a plate having a plurality of slits at each end. Thus, $4-4'-4''$ are narrow slits adjacent to one end and $5-5'-5''$ are narrow slits adjacent to the other end. All these slits are approximately parallel, although the slits $5'$ and $5''$ are preferably in slightly angular relation. They are about one twentieth of an inch in width when used with strips of ordinary muslin.

In Fig. 2 the slits $4-4'-4''$ all open on the same side of the plate, while slit 5 opens on the opposite side from slits $5'-5''$.

In Fig. 3 the construction shown is similar, with the exception that the slits corresponding to 4—4'—4², namely, slits 6—6'—6², open alternately on opposite sides 5 of the plate.

In Fig. 4 the slits on one end are disposed in relations similar to the slits on the other end, the slits 7 and 8 nearest the respective ends opening on opposite sides from their 10 other co-acting slits 7'—7² and 8'—8², the co-acting slits on each end being disposed at an acute angular relation, the slits 7'—8' being substantially parallel to the slits 7 and 8. The sides of the slits 7' and 8' are moreover disposed so as to form acute angles, the apices 9 and 10 of said slits being located at the inner ends of the same.

When my device is in use for holding the 20 ends of a strip, the strip may be passed through the same as shown in Figs. 5, 6 and 7. At the left-hand end of the devices as shown in these figures, the ply which is adjacent to the cigars passes upward through the slit 4. The strip then passes 25 downward through the slit 4', upward through the slit 4², and downward through the slit 4, there being a loose exposed end or ear 11 of sufficient length to be easily grasped. This renders a secure fastening 30 for that end, which is secure even when the strip is not surrounding any bundle, since two of the plies are always held in frictional contact with one another so as not to slip. After this end has been thus secured, the 35 other end of the strip is passed around the bundle and if the strip is of thin or somewhat slippery material, it is passed upward through the inner slit 5², downward through the next slit 5', and upward through the slit 40 5, as shown in Fig. 5, the ear 11 being grasped so as to hold the plate meanwhile. If the strip is of a material which is not 45 so liable to slip, a sufficient holding can be secured by passing the strip upward through the slit 5² and downward through the slit 5', as shown in Fig. 6, or upward through slit 5' and downward through slit 5², as shown in Fig. 7. Similar variations may be made in connection with the form shown in Figs. 3 50 and 4. The angular relation of the slits 5² and 7²—8² to their co-acting slits aids in the binding action of tape passed through the slits.

The slits at either end constitute elongated securing means and all the slits are approximately parallel to one another and approximately perpendicular to a line passing through the center of the plate and intersecting all of said slits, the result being 55 that when the two ends of a tape are secured by the fastening device in the manner shown the tape is maintained flat and when a strain is placed upon the tape the pull comes substantially across the center of the plate.

60 In the device shown in Fig. 4, the tapering

of the slits 7' and 8' enables the device to be used for either holding tapes or holding twine, thus the ends of the twine can be inserted through the slits 7² and 8² and forced toward the apices 9 and 10 respectively, 70 whereupon it will be gripped securely so as to be held in place. In order to more securely hold the twine in place, it is advisable to pass the end extending through the slit 7² into one or both of the slits 7 and 7' 75 and in a similar manner the end of the twine which passes through the slit 8' may be passed through either or both of the slits 8—8'. The hole 12 is for the purpose of hanging the fastening devices upon a pin or peg wherever desired. These fastening devices when used by cigar makers are preferably marked with some designating mark, such as "L" or "R," which will indicate 80 whether the cigar maker is working upon rights or lefts and are also marked with numerals such as 20 or 21, which will identify the cigar maker who made the cigars in the particular bundle which bears any given fastening device. This enables the bundles containing rights to be easily identified and separated from the bundles containing lefts for the purpose of guiding the packer, and also identifies the maker so that he can be held responsible for any defective work. 90

As will be evident to those skilled in the art, my invention permits of various modifications without departing from the spirit thereof or the scope of the appended claims.

What I claim is:

1. A fastening device consisting of a plate having a plurality of slits adjacent to each of its ends, said slits being approximately parallel to one another and approximately perpendicular to a line passing through the center of said plate and extending across that line. 105

2. A fastening device consisting of a plate having elongated securing means at one end and three approximately parallel slits adjacent to the other end, said securing means extending across a line intersecting each of said slits at approximately a right angle and passing approximately through the center of said plate. 110

3. A fastening device consisting of a plate having elongated securing means at one end and three approximately parallel slits adjacent to the other end, the slit nearest said other end opening on one side and the other 120 slits opening on the other side of said plate, said securing means lying in a line intersecting each of said slits at approximately a right angle and passing approximately through the center of said plate. 125

4. A fastening device consisting of a plate having elongated securing means at one end and three approximately parallel slits adjacent to the other end, the slit nearest said other end opening on one side and the other 130

slits opening on the other side of said plate, said other slits being at an acute angle to one another, their inner ends being nearer together than their outer ends.

5 5. A fastening device consisting of a plate having a plurality of slits adjacent to each of its ends, said slits being approximately

parallel to one another and approximately perpendicular to a line passing through the center of said plate and intersecting all of 10 said slits, the sides of one of the slits at each end forming an acute angle whose apex is at the inner end of its slit.
